ABSTRACT OF THE DISCLOSURE

Printing apparatus in the form of a stencil duplicator in which the movement of the pressure roller towards and away from the printing roller is controlled by a pneumatic system comprising a pulse pump communicated with a pneumatic motor by way of a rotary vent valve. The valve is operated by a pivotable sheet sensing lever and the pneumatic motor is engageable with a control lever to connect it operably with a reciprocating member only when a sheet is present. The control lever is mounted on a swinging support for the pressure roller to thus control movement of the pressure roller.

The present invention relates to sheet feeders and more particularly to apparatus for feeding sheets one at a time to associated equipment where it is important that such equipment or part of it should be inoperative when no sheet is being fed thereto. One form of equipment in which the sheet feeder of this invention is particularly useful is a stencil duplicator. In stencil duplicators, the stencil is carried around a printing cylinder, and sheets of paper are passed one at a time between the stencil on the printing cylinder and a pressure roller which presses the paper against the stencil. It is necessary for the pressure roller to move towards and away from the printing cylinder as each sheet of paper is being fed through the duplicator and also for the pressure roller to be prevented from moving towards the printing cylinder when no sheet is being fed through the duplicator. If such movement were not prevented, the pressure roller would contact the stencil and be inked thereby and then cause soiling of the backs of the sheets subsequently passed through the duplicator.

Conventional stencil duplicators have been provided with a paper detecting device which, by means of a mechanical linkage to the pressure roller movement mechanism, ensures that the movement of the pressure roller is only effected when a sheet is being fed. In our British Pat. No. 973,108 we have described an improved paper detecting and pressure roller control device in which control of the pressure roller is effected by pneumatic means under the control of means which senses when paper is not being fed through the machine. In the construction described in our said patent, the sensing device comprises a detector piston and cylinder arrangement which is positioned above the feed path of sheets to the printing cylinder and to which, while the duplicator is in operation, alternate pressure and suction pulses are supplied from a master piston and cylinder arrangement operated in synchronism with the operation of the duplicator to cause the detector piston to move downwardly and then upwardly again, once for each cycle of operation

2

of the duplicator. The detector piston is positioned so that, in moving to its lowermost position, it crosses the feedpath of sheets fed to the printing cylinder. When no sheet of paper is being fed to the printing cylinder at the time the detector piston moves downwardly, this piston moves to its lower-most position and in such position permits a pressure pulse of air from the master cylinder to be fed to pressure roller control means. This pressure pulse acts to effect disconnection of the mechanism which normally causes the pressure roller to engage the printing cylinder of the duplicator at the appropriate time during each printing cycle. When, however, paper is being fed to the printing cylinder at the time the detector piston moves downwardly, such piston is intercepted by the paper and prevented from reaching its lowermost position. As a consequence, no pressure pulse of air can be sent to the pressure roller control means and the pressure roller operates normally.

It is an object of this invention to provide in a sheet feeding apparatus a paper detecting device which may be used to provide pneumatic operation of a mechanism, such as a pressure roller control mechanism as in the case of the construction of our said prior patent, but is improved as compared with such construction.

Although in the above we have referred particularly to the use of the paper detecting device in the sheet feeder of a stencil duplicator for providing control of the pressure roller of such duplicator, it will be appreciated that this is an illustration only of the use of such device. It may equally well be used in a sheet feeder associated with any other apparatus for controlling operation of the latter or of part thereof; for example, it could be used in the sheet feeder associated with a rotary offset duplicating machine for controlling the printing and blanket cylinders thereof.

According to this invention, there is provided, for use in sheet handling equipment, a paper detecting and equipment control device comprising pneumatically operable means adapted to control the actuation of the said equipment or of part thereof, means for producing pressure pulses at a pressure different from atmospheric for operating the said pneumatically operable means, a guide for guiding a sheet to sheet equipment and a valve controlling the application of said pulses to the pneumatically operable means, such valve having an actuating member biased to a position in which it prevents the application of said pulses to the pneumatically operable means, but arranged so as to be engaged by a sheet of paper as it passes over such guide, so that it is moved by such paper sheets to actuate the valve so that said pressure pulses are applied to the pneumatically operable means.

In the construction according to this invention, the equipment or part thereof controlled by the pneumatically operable means can only be actuated upon receipt of a positive signal that a sheet of paper is passing to the equipment. Thus, since the equipment or relevant part thereof is not normally actuated and is only caused to operate when paper passes to the equipment, any failure of the device will not lead to the equipment being fully operated while no paper is being fed thereto.

Thus, in the case where the device according to this invention is applied to the sheet feeder of a conventional stencil duplicator with the pneumatically operable means controlling the actuation of the pressure roller of the duplicator, the pressure roller can only be actuated when a positive signal has been received that a sheet of paper

is passing to the printing cylinder. Since the pressure roller is not normally actuated and is only caused to operate when paper passes to the printing cylinder, any failure of the device will result only in sheets which are fed through the duplicator passing through without being pressed against the printing cylinder and will not lead to the pressure roller being engaged with the stencil on the printing cylinder of the duplicator. In the construction described in our British Pat. No. 973,108, since the pressure roller is normally operated at each cycle of the machine and the control device acts to prevent operation of the pressure roller when no sheet is being fed, failure of such construction would be accompanied by engagement of the pressure roller against the stencil on the printing cylinder when no sheet is being fed.

Preferably, according to a further feature of the invention, the valve is of the rotary type in which pivoting of the actuating member operates the valve, the member projecting into the feed path of sheets to the associated equipment so that a sheet being fed thereto will swing the member aside and thereby actuate the valve.

Although the valve could be arranged directly in a conduit from the means for producing pressure pulses to the pneumatically operable means so as to control the opening and closing of such conduit, advantageously, according to a further feature of the invention, the valve is in a branch passage from such a direct connection and the valve operates either to close such branch passage so that the pressure pulses are applied to the pneumatically operable means or to open such branch passage to the atmosphere so that the pneumatically operable means is not operated.

Conveniently, the pressure pulses are produced by a master piston and cylinder arrangement actuated in synchronism with the operation of the equipment, e.g. in the case of a stencil duplicator from a cam provided on the main drive shaft of the duplicator.

According to a further feature of the invention, the pneumatically operable means preferably comprises a piston and cylinder arrangement to which the pressure pulses are applied when a sheet is fed to the equipment, such piston and cylinder arrangement being adapted to effect the desired operation of the equipment or part thereof. Where the device is applied to the sheet feeder of a stencil duplicator, the piston and cylinder arrangement is advantageously adapted to pivot a control lever into the path of a member moving in synchronism with the operation of the duplicator, so that such control lever is moved by such member to effect movement of the pressure roller of the duplicator.

Although, as indicated above, the pneumatically operable means may be such as to be operated by suction, we prefer to use air under a positive pressure.

In order that this invention may more readily be understood, one embodiment of a paper detecting device according to the invention applied to the sheet feeder of a stencil duplicator will now be described, merely by way of example, with reference to the accompanying drawing, in which:

FIG. 1 is a schematic illustration of a duplicator including the device in the condition when no sheet is being fed through the duplicator;

FIG. 2 shows a cross-section on the line II-II of FIG. 1 to show the position of the valve;

FIGS. 3 and 4 are views corresponding to FIGS. 1 and 2, but illustrating the condition when a sheet is passing through the duplicator; and

FIG. 5 illustrates how the operation of the slave piston and cylinder arrangement causes operation of the pressure roller.

The embodiment of device illustrated in the drawing is for the sheet feeding mechanism of a conventional stencil duplicator of the twin cylinder type, i.e. the type which comprises two cylinders mounted on parallel axes

spaced one above the other, an ink screen over which the stencil is adapted to be placed passing around these two cylinders. The sheet feeding mechanism is provided for passing copy sheets of paper between the lower or printing cylinder, of the two cylinders and a pressure roller mounted below such printing cylinder. However, as indicated above, the device can equally be applied to any form of sheet handling apparatus.

The synchronising of the various ancillary mechanisms of the duplicator, such as the sheet feeding mechanism, with the rotation of the cylinders is effected by these mechanisms being driven from a cam or cams on the main driving shaft 32 of the duplicator. In the duplicator of this invention, such shaft 32 has two additional cams, namely an operating cam 6 for a master air piston and cylinder arrangement and a pressure roller drive cam 14.

The follower for the cam 6 is a roller 15 carried by a pivoted lever 16, such lever engaging a boss 33 on a master piston 4 which is slidable in a master cylinder 5. The piston 4 is reciprocable within the cylinder 5, being forced downwardly into the cylinder by the cam and follower and upwardly again by a helical return spring 17. At a position near the top of the wall of the cylinder 5, the latter is provided with an aperture 18 which, in the upper position of the piston 4 registers with an aperture 19 in the wall of the piston. The lower part of the interior of the cylinder 5 communicates with a side chamber 20 provided with outlets 21 and 22. During operation of the duplicator at each cycle of the machine, the piston 4 is depressed within its cylinder, tending to build up pressure in the side chamber 20, and is then returned by the spring 17 to the position shown in FIG. 1, at which time the interior of the cylinder is vented to atmosphere through the then registering apertures 19 and 18.

The outlet 21 of the side chamber 20 is connected by a gas-tight conduit 23 to the interior of a hollow valve body 24 which is generally of cylindrical form. Rotatably mounted on the valve body 24 is a sleeve 25 carrying a thin metal finger 1 forming the sensing member which senses when a sheet is being fed through the duplicator. The shape and position of the finger 1 is such that it normally rests in the position shown in FIG. 1 under gravity against the paper fence 2. In this position, an aperture 3 in the finger and sleeve 25 registers with a cross bore 34 in the valve body 24 and vents the outlet 21 of the side chamber 20 to the atmosphere. Pivoting of the finger 1 upwardly from the positions shown in FIGS. 1 and 2 by a sheet of paper passing through the duplicator will cause the aperture 3 to move out of register with the cross bore of the body 24 and the outlet 21 thereby to be closed.

The outlet 22 of the side chamber 20 of the master cylinder 5 leads via a conduit 26 to a slave piston and cylinder arrangement 7, the piston of which engages against a roller 26 mounted on a control lever 8 which is pivoted on a pin 9 carried by a pressure roller lifting lever 10 (see FIG. 5). In this condition, the control lever 8 rests against a stop 11. The pressure roller lifting lever 10 is pivotally mounted on a pivot 27 on which is also pivoted a two-armed lever 13 having at the end of one arm a follower 28 engaging the cam 14 and at the end of the other arm a peg 12 projecting through a slot 29 in the pressure roller lifting lever 10.

In operation of the machine, the cam 14 moves the two-armed lever 13 so that the peg 12 reciprocates along an arcuate path centered on pivot 27. With the control lever 8 in the position shown in FIGS. 1 and 2, the peg 12 moves from the position shown in full lines in FIG. 1 to the position shown in dotted lines in the same figure. It will be seen that this movement of the peg 12 is between two limbs 30 and 31 of the lever 8 and does not affect the angular movement of such lever. When, however, the piston of the slave piston and cylinder arrange-

ment 7 moves to the position shown in FIG. 3 and, by its engagement with the roller 26, pivots the lever 8 about pin 9 from the position shown in FIG. 1 to that shown in FIG. 3, the limb 30 engages the stop 11 and the limb 31 moves into a position obstructing the arcuate path of the peg 12. Reciprocation of the peg 12 then will move the lever 8 between the full and dotted line positions shown in FIG. 3. Such movement of the lever 8 would be transmitted to the pressure roller lifting lever 10 by virtue of the connection between the levers provided by the pivot 9.

The operation of the above-described device is as follows:

The normal condition of the device is that shown in FIGS. 1 and 2 and the device retains this condition unless a sheet of paper engages the finger 1. With the device in this condition, the side chamber 20 is vented to the atmosphere through conduit 23 and aperture 3 in the rotary valve. At each cycle of the duplicator the cam 6 causes the depression of the master piston 4 in its cylinder 5 but, because the chamber 20 is vented to the atmosphere, no pressure build-up occurs in the master cylinder 5 and the slave piston and cylinder arrangement 7 is unaffected. The lever 8 remains in the FIG. 1 position; the peg 12 which reciprocates once for each cycle of the duplicator engages between limbs 30 and 31 and does not affect the lever 8 and the pressure roller lifting lever 10 is also unaffected.

When, however, a sheet of paper 35 passes through the duplicator, as shown in FIGS. 3 and 4, this sheet 35 lifts the sensing finger 1 and closes the rotary valve by moving aperture 3 out of register with cross bore 34. The chamber 20 is then no longer vented to the atmosphere and the depression of the master piston 4 in its cylinder 5 causes a build-up of pressure therein which is transmitted to the slave piston and cylinder arrangement 7 and moves the lever 8 into the position shown in full lines in FIG. 3. The pin 12 in its reciprocation engages the lever 8 and moves this laterally to the dotted line position shown in FIG. 3, movement of the lever 8 thereby moving the pressure roller lifting lever 10 which effects lifting of the pressure roller 36 towards the printing cylinder 38 so as to press the sheet of paper 35 against the stencil passing round the printing cylinder.

It will be appreciated that, if the above-described device fails to operate, the pressure roller 36 will not be raised and there will be no question of such roller coming into contact with an inky stencil. Further, the operation of the device cannot be obviated by hand turning of the machine very slowly as is sometimes possible with the construction of our previously mentioned British patent specification. Additionally, the rotary valve 25, the sensing finger 1, the piston of the slave piston and cylinder arrangement 7 and the control lever 8 are stationary when the machine is idling and thus unnecessary wear of such parts is avoided, and the device is quiet in operation since it does not have a detector piston constantly reciprocating into the path of the sheets fed through the duplicator. The device according to this invention allows the machine to be operated by hand feeding if desired.

It is conventional for the stencils which are used with stencil duplicators to be provided with a backing sheet of stiff paper. When the stencil is initially laid on the ink screen, the operator rotates the stencil and attached backing sheet at least once so that the pressure roller may lift and press the backing sheet onto the stencil so that the stencil is properly inked, the backing sheet being torn off thereafter. In conventional duplicating apparatus, a button is provided to override the action of the mechanical sheet detector so that the pressure roller is caused to rise even though no paper is passing through the duplicator.

In the sheet detecting and pressure roller control device of this invention, provision may also be made for

enabling the pressure roller to rise when desired, e.g. when wishing to press a backing sheet against a stencil, even though no paper is passing through the duplicator.

When the backing sheet button (not shown) is depressed it engages the upper surface of the limb 31 of lever 8, and pivots the lever to the position shown in FIG. 3. When in this position the pressure roller is raised even when no paper is fed, and the backing sheet is pressed against the stencil.

I claim:

1. Sheet printing apparatus comprising:

- (a) a printing roller;
- (b) a pressure roller disposed parallel to said printing roller;
- (c) pivotable operating lever means carrying said pressure roller for movement towards and away from said printing roller;
- (d) a reciprocating member driven in synchronism with the operation of said sheet printing apparatus for movement along a path;
- (e) a control lever pivotally mounted on said operating lever means for movement between a first normal position wherein it lies clear of said path and a second operating position wherein it lies on said path for operable engagement by said reciprocating member;
- (f) a sheet guide;
- (g) means driven by said sheet printing apparatus for creating a pressure pulse at a pressure different from atmospheric;
- (h) pneumatic motor means positioned for operable engagement with said control lever to move said control lever from said first to said second positions;
- (i) conduit means joining said pressure pulse creating means to said pneumatic motor means;
- (k) a sensing lever biased towards a first angular position and pivotable to a second angular position by contact with a passing sheet along said guide; and
- (l) a rotary vent valve operably connected to said sensing lever and communicating with said conduit means for rendering said pressure pulse creating means operative on said pneumatic motor means only when said sensing lever is in its second angular position, and for venting said conduit means when said sensing lever returns to its first angular position.

2. Sheet printing apparatus according to claim 1, and including a main drive shaft, a first cam on said main drive shaft for operating said pulse creating means, and a second cam on said main drive shaft for driving said reciprocating member.

3. Sheet printing apparatus as claimed in claim 1, wherein said conduit means comprises a first conduit extending between said pneumatic motor and said pulse creating means, and a second conduit forming a branch passage from said first conduit, said rotary vent valve being positioned in said second conduit and operating either to close said branch passage or to open said branch passage to the atmosphere.

4. Sheet printing apparatus as claimed in claim 1, wherein said pressure pulse creating means comprises a master cylinder and a master piston operably connected to said sheet printing apparatus for driven reciprocation within said master cylinder.

5. Sheet printing apparatus according to claim 1, wherein said pulse is at a pressure above atmospheric pressure.

6. Sheet printing apparatus as claimed in claim 1, wherein said pneumatic motor means comprises a slave piston and a slave cylinder to which the pulse is applied only when said sensing lever is in its second angular position, said piston being slidable within said slave cylinder and being in operable engagement with said

control lever to effect movement of said control lever between said first and second positions.
